UNITED STATES PATENT OFFICE

WILLIAM H. BRIGHT, OF OZONE PARK, NEW YORK

GOLF-BAG SUPPORT

Application filed September 7, 1929. Serial No. 391,016.

This invention relates to improvements in golf bag supports.

The primary object of the invention is to provide a foldable support for supporting a golf bag in an inclined standing position during the playing of the game of golf to permit the player to remove the selected club from the bag and return the same thereto for eliminating the usual and tiresome practice of dropping the bag on the turf during each shot and then bending over to pick up the same.

Another object of the invention is the provision of a golf bag support which includes a pair of crossed legs which automatically drop against the side of the bag upon lifting of the bag and remain thereagainst during carrying of the bag.

A further object is to provide a golf bag support which may be carried in the bag when not in use without materially increasing the weight thereof, and which may be readily connected to the bag when desired.

A still further object is to provide a golf bag support which is simple in construction, inexpensive of manufacture, and strong and durable for the purpose intended.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is a perspective view showing my improved support in position upon the golf bag with the support in an operative position.

Figure 2 is a side elevational view showing the support in a folded position.

Figure 3 is an enlarged detail sectional elevational view through one of the pivotal connections.

Figure 4 is a detail fragmentary perspective view of the manner in which the crossed legs are held in an extended position.

Figure 5 is a detail perspective view of a modified form of eye nut.

Referring to the drawings by reference characters, the numeral 10 designates a golf

bag of the ordinary well known construction which is used for the carrying of golf clubs 11 during the playing of the outdoor game of golf. It will be appreciated that at present it is the practice of golfers who are obliged to 55 carry their bags, to drop the same upon the turf after removing the desired club from the bag during each shot, which practice necessitates the bending over to pick up the bags after each shot, which eventually becomes 60 tiresome and in some instances affects the golfer to such an extent to interfere with the experts view required in making a low score. To overcome this objection I have constructed a support which may be instantly moved to a 65 position to rigidly support the bag in an inclined upstanding position to permit the golfer to remove the desired club from the bag and to return the same thereto after use of the club, and whereupon lifting of the bag will cause the support to automatically hold 70 to a position flat against the sides of the bag and remain in such position during carrying of the same. The invention therefore includes a pair of flat headed bolts 12—12 which 75 pass through the side walls of the bag adjacent the open top thereof so that the head of the bolt is disposed within the bag while the threaded shanks extend outward and receive jamb nuts 13 which screw tightly against the 80 exterior walls of the bag. These bolts 12 are diametrically disposed and serve as pivot bolts for a pair of relatively light leg members 14—14, the top ends of which are provided with screw eyes 15 which fit over the 85 projecting ends of the bolt 12 and which are detachably connected thereto by button nuts 16 which thread on the outer free ends of the bolt. Although I have described one method 90 of pivotally connecting the upper ends of the legs 14 to the bag, I have shown in Figure 5 a modified form of nuts 17 which threads to the shank of the bolt and is provided with an eye 18 to which the screw eye 15 of the respective legs may be loosely connected. Mounted adjacent the top of the bag intermediate the pivot bolts is a third bolt 19 which likewise receives a jam nut, while the free threaded end of the bolt receives a button nut 20 which retains the upper end of a flex-

100

ible chain 21 to the bag. The lower end of the chain 21 carries a snap hook 22 for detachable engagement with an eye 23 fixed to the bag adjacent the bottom end thereof. Although a chain has been shown in the drawing, it will be appreciated that any other type of flexible element may be substituted therefor if desired.

The legs 14—14 are crossed as clearly shown in Figures 1, 2 and 4 of the drawings, while slidably mounted thereon below the point of intersection of the said legs is a ring member 24 which is also slidable on the chain 21 which chain captively secures the said ring to the legs for a purpose to be presently explained.

In practice, assume that the support is in a folded position against the side of the bag as shown in Figure 2 of the drawing and it is desired to extend the legs to support the bag in the position shown in Figure 1. To extend or open the legs to the position shown in Figure 1, it is only necessary for an operator to slide the ring member 24 upwardly upon the legs 14 which causes them to spread and by swinging the said legs away from the bag, the said bag may be firmly supported in a substantially vertical position to permit the player to remove the desired club from the bag and return the same thereto after use of the club. By lifting the bag from the ground or turf the ring member 24 will drop by gravity causing the legs 14 to be retracted and swing to a position flat against the sides of the bag 10. It will therefore be seen that the legs may be moved to a supporting position by merely actuating the ring member 24 and the same automatically folds to a closed position upon lifting of the bag after each use of the support.

I have found it perfectly satisfactory to employ relatively light round rods for the legs 14 in order to reduce the weight of the support, but if desired the said legs may be constructed of hollow metal tubes without materially increasing the weight. When not in use, the retaining nuts 16 may be removed and the legs uncoupled from their respective pivot bolts after disconnecting the hook 22 from the eye 23 whereupon the legs may be placed within the bag together with the flexible element or chain 21.

While I have shown and described what I believe to be the best embodiment of my invention, I do not wish to limit myself thereto as certain changes may be made as come within the scope of the same if desired.

Having thus described the invention, what I claim as new and desire to secure by Letters Patent is:—

1. In combination with a golf bag, a pair of cross legs pivoted thereto, a flexible element secured to the bag at opposite ends, and a ring member slidably mounted on said cross legs and chain.

2. In combination with a golf bag, a pair of cross legs pivoted thereto adjacent the top thereof, and a ring member slidably and captively mounted to said legs.

3. In combination with a golf bag, a pair of cross legs pivoted thereto at diametrically opposite points, adjacent the top of said bag, a flexible chain secured to and extending lengthwise of said bag, and a ring slidably mounted on said legs and chain for retaining said legs in a crossed condition and for holding the same against spreading when in a set up supporting position.

4. A golf bag support comprising a pair of crossed legs adapted to be pivotally connected adjacent the top of a golf bag, a chain adapted to have its ends secured to a golf bag, and a ring member slidable over said crossed legs and ring member.

5. A golf bag support comprising a pair of pivot bolts adapted to be mounted adjacent the top of a golf bag, a pair of crossed legs provided with eyes at one end for pivotal connection with said pivot bolts, a chain adapted to be fixedly connected at opposite ends to a golf bag, and a ring for sliding movement on said chain and crossed legs below the point of intersection thereof.

In testimony whereof I affix my signature.

WILLIAM H. BRIGHT.
